UNITED STATES PATENT OFFICE.

WILLIAM P. UNDERHILL, OF EAST ROCHESTER, NEW YORK.

ROLLING WINDOW-SCREEN.

1,151,424.

Specification of Letters Patent. Patented Aug. 24, 1915.

Application filed August 3, 1914. Serial No. 854,812.

To all whom it may concern:

Be it known that I, WILLIAM P. UNDERHILL, a citizen of the United States, residing at East Rochester, in the county of Monroe and State of New York, have invented certain new and useful Improvements in Rolling Window-Screens; and I do hereby declare the following to be a full, clear, and exact description of the invention, such as will enable others skilled in the art to which it appertains to make and use the same.

This invention relates to rolling window screens, and one of the principal objects of the invention is to provide simple, reliable and efficient means for connecting a window screen to a spring actuated roller and for mounting the roller underneath a hood at the outside of the window and means for connecting the lower edge of the screen material to a strip or roller having its ends reduced and mounted in guide ways in the sides of the window frame, so that the screen may be readily moved up and down and connected to the window sill when lowered in position for use.

The foregoing and other objects may be attained by means of the construction illustrated in the accompanying drawings, in which,

Fig. 1 is a front elevation of the upper portion of the rolling window screen with the hood or cover removed. Fig. 2 is a similar view in which the cover or hood is shown in place, Fig. 3 is a vertical sectional view taken through the roller and the hood, Fig. 4 is a similar view looking at the opposite end of the roller, Fig. 5 is a detail sectional view of one of the guide ways for the roller at the end of the screen material, and Fig. 6 is a plan view of the bracket for the squared pintle of the screen roller.

Referring to the drawings, the numeral 1 designates a window shade roller of ordinary construction, and 2 is the bracket secured outside to the window frame, and provided with a rectangular pintle bearing 3 for the squared pintle of the roller. Upon the opposite side of the window frame is a bracket 4 having a round bearing for the

round pintle 5. Wound upon the roller 1 is 50 the screen material which may be fastened to the roller in any suitable manner and the lower edge of the screen material is connected to a cross rod or bar in the form of a roller 6 having end reduced smooth portions 7 mounted to slide in metal guide ways 8 secured at the opposite sides of the window frame. The guides 8 are preferably formed of metal and the guide ways or recesses 9 are formed by bending the sheet 60 metal inward in substantially U-shape and providing two laterally extending feet to be connected to oppositely disposed cleats 10 and said feet and cleats are connected to the window frame outside the window by 65 means of suitable fastenings 11. The screen material is designated by the letter *a*.

Extending over the roller carrying the screen material is a hood or protector 12 which is secured to the window casing by 70 means of a plate 13 and suitable fastenings 14. The hood 12 is provided with end tabs or covers 15. The roller or cross bar 6 is provided with a ring 16 designed to be connected to a pin or nail secured to the window sill at the lower portion thereof. The roller 6 being substantially the length represented by the distance between the two guide members 8 will prevent any side movement or irregular winding of the screen 80 material upon the roller 1, and will insure a smooth action of the screen material.

From the foregoing it will be obvious that a window screen made in accordance with this invention can be rolled up out of the 85 way when not required for use, and can be quickly drawn down and secured whenever required.

Various changes may be made in the details of construction without departing from 90 the spirit and scope of the invention as defined in the claim.

What is claimed is:—

The herein-described rolling window screen comprising a window shade roller, window 95 screen material connected to said roller, a bar having oppositely extending pins, the edge of said screen material being secured

to said bar, metal guide-ways connected to the opposite sides of the window frame, said metal guide-ways being bent into U-shape with oppositely projecting feet, cleats connected to said feet and said feet and cleats connected to a window frame to form guides for said pins.

In testimony whereof I affix my signature in presence of two witnesses.

WILLIAM P. UNDERHILL.
